ABSTRACT OF THE DISCLOSURE

In a writing tool such as a ball-point pen with a writing insert which is adapted to be moved within a casing so as to project therefrom or to be fully retracted therein, an improved actuating mechanism in which the element which locks the relatively movable parts together consists of a rocker. For counteracting fatigue of the material of the rocker, the invention provides an additional spring element the resilience of which assists in bending the rocker back to its normal inactive position. This spring element preferably consists of the return spring which acts upon the writing insert.

The present invention relates to a writing tool and especially to a ball-point pen which comprises at least one lead, ink carrier or ball-point refill (hereafter collectively referred to as "lead") which is slideable in its axial direction within a tubular casing, and a pressure-actuated mechanism for advancing and retracting the lead so that its writing point projects or is withdrawn from the front opening of the casing and for arresting the lead in the advanced and retracted positions. This mechanism comprises two main components which are movable relative to each other in the axial direction of the casing and one of which is a pressure-applying element, for example, a pushbutton, which acts upon the lead and is advanced and retracted against or under the action of a retracting spring, respectively, while the other component is the tubular casing. One of these components, preferably the pressure-applying element, is provided and preferably integral with a rockerlike member which may be bent resiliently from a normal position in a radial direction relative to the longitudinal axis of the casing and, if the pressure-applying element is nonrotatably mounted in the casing, also in a peripheral direction. This rocker carries a control cam which, when the pressure-applying member is moved, cooperates with guide edges which are provided on the other component and is thereby moved to two arresting positions which are associated with the advanced and retracted positions of the lead and are located above or behind each other, as seen in the longitudinal direction of the casing.

If such a mechanism is made of plastic as it is very often done today, there is the possibility that after frequent bending of the rocker its material will show signs of fatigue, especially if the rocker has remained for a longer period in its bent position away from the normal position. The reduction in the elasticity of the rocker due to fatigue may seriously impair the proper function of the mechanism. It is therefore the principal object of the present invention to prevent the occurrence of such a fatigue of the material as much as possible. For attaining this object, the invention broadly consists in the provision of a spring element which assists in bending the rocker back to at least one of its normal positions.

According to one preferred embodiment of the invention this is attained by designing the spring which moves the pressure-applying element to its retracted position so as also to serve as a resilient element for bending the rocker back to its normal position. It is, however, also

2

possible to employ a separate spring element between the foot of the rocker and the pushbutton which is adapted to take up substantially the tensions which are produced when the rocker is being bent and which forms the pivot joint for the rocker. Of course, these two functions may also be carried out by the same element.

While with a pushbutton which is rotatably mounted it will generally suffice if the spring element supports the radial movement of the rocker in the direction toward its normal position, it is advisable when the pushbutton is nonrotatable to design the spring element so as also to tend to counteract and reverse the peripheral deflection of the rocker.

According to the invention, the fatigue of the material is counteracted also by making the guide edges which cooperate with the control cam and are preferably provided on the wall of the casing of a novel and advantageous design. The invention is for this purpose based on the concept that the guide edges should be designed so that, when the lead is in its advanced position, the rocker should be bent only very slightly in the peripheral direction relative to the position in which it is located in the retracted position. One of the features of the invention for accomplishing this object consists in providing two guide edges which are located above each other, as seen with reference to the longitudinal axis of the casing, and are inclined in the same direction and are provided at their rear end near the rear end of the casing with an arresting position for the control cam for holding it in the retracted position or in the advanced position of the lead. The arresting position which is provided on the lower guide edge is offset, preferably for a distance less than the width of the cam, relative to the arresting position on the upper guide edge in the direction toward the end of the upper guide edge which is most remote from the rear end of the casing. Another feature of the invention for attaining the above-mentioned object consists in providing at least one stop edge which extends in the longitudinal direction of the casing and prevents the rocker when passing from the upper guide edge to the arresting position on the lower guide edge from pivoting beyond this position. Another feature of the invention consists in providing a releasing edge which is located underneath the lower guide edge and bends the cam which is pressed against it so far back in a radial direction that it will be moved to a position outside of the range of action of the stop edge which extends in the longitudinal direction. A further feature for attaining the above-mentioned objects consists in providing a control cam which extends substantially in a radial direction and has on its lower side a work surface which cooperates with the uppermost guide edge and on its upper side a work surface which cooperates with the guide edge underneath thereof. The term "cam" as used herein in connection with the invention is intended to mean any kind of radial projection.

For simplifying the manufacture and assembly of the writing tool according to the invention, it is another of its features to provide the guide edges on an extension of the casing which projects from the rear end thereof and is preferably integral therewith and only partly surrounds the pressure-applying element, for example, the pushbutton, preferably to an extent less than one half of its peripheral surface. When designing the writing tool in this manner, the advantage is attained that the component of the mechanism on which the guide edges are provided may be much more easily molded than when these edges are provided on a peripherally closed part, for example, on the casing of the writing tool itself.

The features and advantages of the present invention will become more clearly apparent from the following detailed description thereof which is to be read with reference to the accompanying drawings, in which—

FIGURE 1 shows a longitudinal section of the rear part of the casing of the writing tool with the operating mechanism therein;

FIGURE 2 shows a view similar to FIGURE 1 but taken from one lateral side thereof;

FIGURE 2a shows a modification of the embodiment depicted in FIGURE 2.

FIGURE 3 shows an enlarged side view, as seen from the right of FIGURE 2, of the part of the casing in which the guide and releasing edges as well as a part of the stop edges for the control cam are formed by apertures in the wall of the casing;

FIGURE 4 shows a cross section which is taken along the line IV—IV of FIGURE 3;

FIGURES 5 and 6 show two views similar to FIGURE 4, in which the control cam is shown in two different operating positions;

FIGURES 7 and 9 show cross sections which are taken along the line VII—VII of FIGURE 3, in which the cam is shown in three other operating positions;

FIGURE 10 shows a view similar to FIGURE 3, in which the cam is illustrated in the same position as shown in FIGURE 8;

FIGURE 11 shows a view of the inside of part of the casing of a writing tool according to a modification of the invention in which the guide edges are provided by projections on the inner side of the casing;

FIGURE 12 shows a side view of a modification of the pushbutton which is provided with a resilient member between the foot of the rocker and the actual pushbutton;

FIGURE 13 shows a side view of the pushbutton according to another modification of the invention;

FIGURE 14 shows a side view of the rear end of a writing tool according to another modification of the invention, in which the guide edges are provided on an extension of the casing;

FIGURE 15 shows an enlarged side view similar to FIGURE 3 of a further modification of the invention;

FIGURE 16 shows a cross section which is taken along the line XVI—XVI of FIGURE 15; while

FIGURES 17 to 19 show enlarged side views of the control cam according to FIGURES 1 and 2, as seen from different sides thereof.

While in FIGURES 1 to 10 and 17 to 19 the individual parts of the first embodiment of the invention are designated by numerals from 1 to 30, those parts of the five modifications of the invention as shown in FIGURES 11 to 16 which are either equal or functionally similar thereto are designated by the same numerals which, however, are distinguished therefrom by being increased by 100, 200, 300, 400, or 500, respectively.

The actuating or pressure-applying member 1 in the form of a pushbutton is guided in the tubular shank or casing 2 so as to be slidable therein in the axial direction. In the first embodiment of the invention as shown in FIGURES 1 to 11, this pushbutton 1 is prevented from turning within the casing 2 by having a substantially square cross section in accordance with the shape of the casing 2. The lower end of the pushbutton 1 has eccentrically thereon an extension 4 which is connected by an arm 6 to a rocker 5 which extends parallel to the axis of casing 2. The parts 1, 4, 5, and 6 may be integral with each other and consist of a resiliently deformable molded piece of plastic so that the rocker 5 may be resiliently bent or pivoted in the radial direction as indicated by the arrow A in FIGURE 2 and also in the peripheral direction as indicated by the arrow B in FIGURE 1. For bending the rocker 5 in the peripheral direction, the extension 4 serves as a flexible joint similar to a leaf spring.

Arm 6 of the mentioned plastic element has an obliquely inclined lower side 6'. When a pressure is exerted upon this inclined side 6', a torque with a lever arm c is exerted upon the rocker arm 5 which acts in the peripheral direction. In the embodiment as illustrated in FIG-

URES 1 and 2, this torque is produced when the rear end of the lead 7 is pressed by the return spring 8 against this inclined surface 6'. In FIGURE 1, the rocker 5 is in its normal inactive position in which its upper end carrying a cam 9 as subsequently described will be pressed by the action of spring 8 against the wall of casing 2. When the pushbutton 1 is being depressed and the rocker 5 is bent from its normal position in the peripheral direction by a deformation of the extension 4, not only the torque will occur which is caused by the mentioned lever action but also an additional torque which is produced by the resilience of the material. If the spring part, for example, the part 204 in FIGURE 12 which is provided between the lower end of the rocker 5 and the pushbutton 1 is made of a suitable shape, the resilient force which is produced by the deformation of the material may alone be sufficient to return the rocker to its normal position. Generally it is, however, advisable also to employ the force of spring 8 acting upon the lead 7 to accomplish this purpose.

In the embodiment of the invention as shown in FIGURES 1 and 2, the rocker 5 is bent in the radial direction against the resilience of its material. This resilient tension may, however, be increased by the tension which is exerted by spring 8 if the surface 6' is suitably inclined.

FIGURE 2a indicates a modification of the rocker arm in the form of a two-armed lever, the upper arm of which is provided with the control cam and the lower arm with the inclined surface 6' which engages upon the rear end of the lead 7 so that a torque will be produced with a lever arm d which exerts an additional force upon the cam carrying arm which tends to bend the latter back to its normal position.

The guide, releasing, and stop edges for the control cam 9 may be designed as illustrated in FIGURES 3 to 10, in which these edges are provided on one side of the wall of a tubular shank or casing 2 which has a square cross section. For forming the guide and releasing edges which are necessary for the operation of the device as subsequently described in greater detail, and for also partly forming the stop edges for the control cam, two parallel slots 10 and 11 are provided at a certain distance above each other in the wall of the casing 2 and are inclined in the same direction relative to the vertical axis of the casing. The lower slot 11 is slightly shorter than the upper slot 10 so that the end of the casing is offset relative to corresponding end of slot 10 at a distance which is smaller than the width of the cam.

Control cam 9 is guided by the lower edge 12 of slot 10 and the upper edge 13 of slot 11. For passing the control cam 9 from slot 10 to slot 11 or from the guide edge 12 to the guide edge 13, the inner side of the wall of the casing is provided with a groove 26 the lateral wall of which forms a stop edge 27 for the cam which guides cam 9 up to the slot 27 which prevents the rocker 5 from pivoting back during its movement from one slot to the other. Edge 28 which limits the slot 11 in the downward direction has an additional guiding purpose, namely, to hold the cam within the slot. At the other side of edge 27, as seen from the groove 26, there is an inclined edge 16 (FIGURE 4) which ascends in the direction toward the edge 27.

At the end of slots 10 and 11 or guide edges 12 and 13 which is closest to the rear end of the casing an arresting corner 14 or 15 is provided for receiving the control cam in the retracted or advanced position of the lead 7, respectively. Each of these arresting corners is formed by the upper corner of the respective slot. In FIGURE 3, the retracted arrested position of cam 9 is indicated in full lines and its advanced arrested position in dotted lines. Underneath the control cam when in its advanced arrested position, slot 11 is provided with a releasing edge 17 which is inclined in the opposite direction to the inclination of guide edge 13 relative to the vertical axis of the casing. In alignment with the arresting corner 14

and parallel to the axis of the casing is a stop edge 30 which is formed by the inner side of the respective side wall portion of the casing.

Control cam 9 is provided on its lower side with a work surface 18 which extends parallel to and overlaps the uppermost guide edge 12 and is located substantially vertically to the plane of rocker 5. The upper side of control cam 9 is provided with an inclined surface 19 which extends in the same direction as guide edge 13 and ascends within the casing from the inside toward the outside and cooperates with the guide edge 13. Cam 9 is further provided with an inclined work surface 20 which extends from the inside toward the outside and is adapted to press the cam against the reversing edge 17.

Cam 9 is further provided with a stop surface 29 which cooperates with the stop surfaces 27 and 30. In the embodiment of the invention as shown in FIGURES 1 to 4, the work surface 20 extends from a point within the upper part of the front side of the cam to a point within the lower part of the rear side of the cam (see FIGURE 2).

The course of movement followed by the control cam during its operation is indicated in FIGURE 3 by a dot-and-dash arrow line. When cam 9 is in the arresting corner 14 (FIGURES 3 and 4) corresponding to the retracted position of the lead 7, and the pushbutton 1 is then depressed, the work surface 18 of the cam will slide along the guide edge 12 (FIGURE 5) until it reaches the end of groove 26 into which it will then enter (FIGURE 6). In the course of this movement of the control cam, rocker 5 is bent from its normal position in the peripheral direction. The rocker will remain thus deflected as long as the cam in passing from the uppermost guide edge 12 to the lower guide edge 13 slides within groove 26 since the surface 29 of the control cam then engages laterally upon the guide edge 27. When the cam enters the slot 11, rocker 5 can swing back so far under the action of the resilient resetting force as produced during its previous deflection that it will abut against the stop edge 28. At this moment, the operator may stop pressing upon the pushbutton 1. Cam 9 will then slide along the edge 28, and its surface 29 will abut against the outer edge 21 of slot 11. During the further retraction of the pushbutton, cam 9 will pass into the arresting corner 15 (FIGURE 9).

If the pushbutton 1 is depressed in the forwardly shifted arresting position, the inclined work surface 20 of the control cam will run against the releasing edge 17. The cam is thereby pushed back in the radial direction (FIGURES 8 and 10). This is due to the fact that the cam is provided with surfaces which extend obliquely from the inside to the outside and from above downwardly. It thus passes out of the range of action of the guide edge 21. Due to the remainder of the resetting force acting upon it, the rocker arm 5 may thereafter swing back to its normal peripheral position. Surface 29 of the control cam then abuts against the edge 30 (FIGURE 9). The movement to this position is assisted by the course of the inclined surface 16 on the inner side of the casing. It may be noted that in this position the rocker arm 5 will be bent resiliently slightly inwardly because its condition of rest corresponds to those positions in which the cam passes through the slots 10 and 11. When the pushbutton is released, cam 9 which is guided on the edge 30 will shift in the opposite direction along a path extending parallel to the axis until it again reaches the slot 10 into which it will then engage under the action of the resilient tension of rocker arm 5. Cam 9 will then again slide into the arresting corner 14 and will thus again be in the retracted position.

It should further be pointed out that in the embodiment of the invention as shown in FIGURES 1 to 10, the bottom of groove 26 and that part of the inclined surface 16 which is directly adjacent to the edge 30 lie substantially within the same plane. Consequently, cam 9

can run along the guide edge 12 only when it is in a position (which also corresponds to the position of rest) which is slightly offset toward the outside relative to that position in which the cam cooperates with the bottom of groove 26. In order to move the cam to this position, the upper end of the rocker is provided with a slight curvature 5a, as indicated in FIGURE 4, which extends in the outward direction. When the pushbutton is being depressed, this part cooperates with the inclined surface 16 which then serves as a guide surface, whereby the rocker is bent inwardly and subjected to a slight elastic deformation. The control cam can then engage into groove 26 when the rocker 5 engages upon the edge which is located at the point of transition from the inclined surface 16 to the stop edge 27.

The rocker 5 is spaced from the pushbutton 1 at such a distance that the latter when in the position as last described will form a stop so that rocker 5 cannot carry out any radial movement of a sufficient amplitude to cause an unintentional release of the control cam relative to the guide edge.

The embodiment of the invention as illustrated in FIGURE 11 has the advantage of being more easily molded since the different edges are provided on projections 122', 122'', and 123. The groove 124 extending parallel to the axis between the projections 122' and 122'' has no importance insofar as the operation of the device is concerned but it is provided for facilitating the molding operation. This groove 124 must, of course, have a smaller width than the cam 109. The reversing edge 117 on the projection 123 is provided with a radially extending inclination which is additionally inclined in the direction of movement of the cam and corresponds to work surface 20 on cam 109 of the embodiment as previously described. When the cam is pressed against the guide edge 117, it will be pressed radially toward the inside and thereby pass again out of the range of the arresting corner which corresponds to the forward arresting position. In addition it should be mentioned that the retracted position of the cam of this embodiment is fixed by special means, for example, by an additional rocker (not shown).

FIGURE 12 shows a pushbutton which is axially slidable within the casing but nonrotatable due to the provision of a projection 203 which engages into a groove 45 in the inner side of the wall of the casing. The resilient element 204 is provided in the form of a torsion rod which extends parallel to the axis between the foot of the rocker 205 and the pushbutton and is integral with the latter. When the rocker 205 pivots in the peripheral direction, the elastic tension which is thereby produced is taken up by the torsion rod so that the material of the rocker itself will not be stressed or even be relieved of stress.

In the embodiment of the invention as illustrated in FIGURE 13, the control cam 309 and the inclined surface 306' against which the rear end of the lead 307 is pressed by spring 308 are provided on the same free end of rocker 305. This arrangement assists in bending the rocker back to its normal position.

While in the embodiments of the invention as previously described the guide, releasing, and stop edges are provided on the wall of a fully closed tubular element, FIGURE 14 shows an embodiment in which these edges are provided on an extension 425 of the rear end of the casing. The guide and releasing edges are in this case formed by slots 410, 411 as in the embodiment according to FIGURE 3. Of course, it is also possible to provide these edges similarly as in the embodiment according to FIGURE 11 by projections which are molded on the side of extension of the casing facing the pushbutton.

FIGURES 15 and 16 show a further embodiment of the invention in which the releasing edge 517 is differently arranged relative to the forward arresting position of the cam than in the embodiment according to FIGURE 3. The reversing edge 517 is located within a line extending parallel to the axis above the position in which cam

is pivoted when leaving the arresting position on the lower guide edge. The inclined work surface 520 of the cam which cooperates with the reversing edge 517 is therefore inclined in the opposite direction to the inclination as in the embodiment according to FIGURE 3. The work surface 520 now ascends from the front side of the cam toward its rear side, as may be clearly seen in FIGURE 16. This drawing also shows that the work surfaces 519, 518 on the upper and lower sides of the cam and also the associated edges on the wall of the casing are inclined so that these work surfaces will engage behind these edges. Thus, the upper work surface 519 is downwardly inclined from its front side toward its rear side, while the lower work surface 518 is upwardly inclined from its front side toward its rear side. This has the result that, when the work surfaces of the cam press against the edges, a force component is produced which draws the cam into the effective range of the edges so that faulty operations will be avoided.

When speaking in the previous description of the invention of the "front side" of the cam, that side is meant which laterally projects from the rocker more than the opposite rear side. This rear side of the cam generally does not project but merges directly with the cam.

Although my invention has been illustrated and described with reference to the preferred embodiments thereof, I wish to have it understood that it is in no way limited to the details of such embodiments but is capable of numerous modifications within the scope of the appended claims.

Having thus fully disclosed my invention, what I claim is:

1. A writing tool having at least one lead slidable in the axial direction within a tubular component and a pressure-actuated device for advancing and retracting the lead point through or from the front opening of the casing of the writing tool, respectively, and for arresting the lead in the advanced or retracted position, said device comprising two operating members movable relative to each other in the axial direction of the casing, one of said members being the pressure-applying element which acts upon the lead and the advancing and retracting movements of which occur against or under the action of a spring, respectively, the other operating member being the tubular component, one of said operating members, preferably the pressure-applying element, being provided with at least one rocker which may be bent from a normal position in a radial direction and thereby produces a resilient resetting force in relation to the longitudinal axis of the casing, and which, if the pressure-applying element is nonrotatably mounted, may also be bent in a peripheral direction, said rocker carrying a control cam which during the movement of the pressure-applying element cooperates with guide edges provided on the other operating member and is thereby passed to arresting positions which are located above each other and are associated with the advanced and retracted positions of the lead, said writing tool further having a resilient element adapted to assist in bending the rocker back to at least one of its two normal positions.

2. A writing tool as defined in claim 1, wherein the resilient element is formed by the spring which acts upon the pressure-applying element.

3. A writing tool as defined in claim 2, wherein the lead is located between the spring and the pressure-applying element against the lower part of which the upper end of the lead engages, said lower part forming an extension of the actual rocker extending in a direction transverse to the axis of the casing and being connected to the pressure-applying element by a joint located outside of the pressure point of the lead lying within the line of force of the pressure, said extension of the rocker forming a lever arm which is pivotable in the axial direction.

4. A writing tool as defined in claim 3, wherein the

contact surface on the rocker for engaging with the lead forms an inclined surface.

5. A writing tool as defined in claim 3, wherein the rocker forms a two-armed lever adapted to be bent in a radial direction and/or in a peripheral direction and having one arm carrying said control cam, while the other arm is provided with the contact surface for the lead.

10 6. A writing tool as defined in claim 1, wherein the resilient element is formed by a flexible joint which is located between the foot of the rocker and the pressure-applying element and is adapted to take up the tensions produced when the rocker is being bent.

15 7. A writing tool as defined in claim 6, wherein the resilient element is integral with the pressure-applying element and with the rocker.

8. A writing tool as defined in claim 6, wherein the resilient element forms a torsion rod extending parallel to the axis of the casing.

20 9. A writing tool as defined in claim 6, wherein the resilient element forms a leaf spring.

10 10. A writing tool as defined in claim 4, wherein the control cam and the inclined surface are provided on the same end of the rocker.

25 11. A writing tool as defined in claim 1, comprising two guide edges located above each other in relation to the vertical longitudinal axis of the writing tool and being inclined in the same direction and each having on its end closest to the rear end of the writing tool an arresting position for the control cam in the retracted or advanced position of the lead, respectively, the arresting position on the lower guide edge being offset, preferably for a distance less the width of the cam, relative to the arresting position on the upper guide edge, as seen in the direction toward the end of the upper guide edge remote from the rear end of the writing tool, said writing tool further comprising at least one stop edge for preventing the rocker when passing from the upper guide edge to the arresting position on the lower guide edge from pivoting beyond said arresting position, a releasing edge located underneath the arresting position on the lower guide edge and adapted to bend the cam when pressed against it so far back in a radial direction that it will be moved to a position outside of the range of the lower arresting position, and a control cam having on its lower side a work surface overlapping the uppermost guide edge underneath.

30 40 12. A writing tool as defined in claim 11, wherein a further stop edge is provided along which the cam slides up to the upper arresting position subsequent to the action of the releasing edge.

50 45 13. A writing tool as defined in claim 11, wherein the work surfaces of the cam cooperating with the upper and lower guide edges are provided with an inclination corresponding to the inclination of the guide edges.

55 14. A writing tool as defined in claim 11, wherein the releasing edge is located within a line extending parallel to the axis of the tool underneath the control cam when the latter is in its forward arresting position.

60 15. A writing tool as defined in claim 11, wherein the releasing edge is located within a line extending parallel to the axis of the writing tool above the position in which the cam is pivoted when leaving the arresting position on the lower guide edge.

65 16. A writing tool as defined in claim 11, wherein the rocker is in its normal position when the control cam is located at the arresting position associated with the retracted position of the lead.

70 17. A writing tool as defined in claim 14, wherein the releasing edge has an inclination extending in the opposite direction to that of the lower guide edge as seen with reference to the vertical longitudinal axis of the writing tool.

18. A writing tool as defined in claim 11, wherein the cam is provided with a further inclined work surface by

means of which the cam may be pressed against the releasing edge.

19. A writing tool as defined in claim 11, wherein the releasing edge is located within a line extending parallel to the axis of the tool underneath the control cam when the latter is in its forward arresting position, wherein the cam is provided with a further inclined work surface by means of which the cam may be pressed against the releasing edge, and wherein the inclined work surface of the cam descends from the front side toward the rear side of the cam.

20. A writing tool as defined in claim 11, wherein the releasing edge is located within a line extending parallel to the axis of the writing tool above the position in which the cam is pivoted when leaving the arresting position on the lower guide edge, wherein the cam is provided with a further inclined work surface by means of which the cam may be pressed against the releasing edge, and wherein the inclined work surface of the cam ascends from the front side toward the rear side of the cam.

21. A writing tool as defined in claim 11, wherein the guide edge provided underneath the lower arresting position has an inclined butting face for the cam on which the latter is bent back.

22. A writing tool as defined in claim 11, wherein the surface against which the cam is pressed when passing from the lower guide edge to the upper guide edge has an inclination adapted to assist in pivoting the rocker in the direction corresponding to the retracted arresting position.

23. A writing tool as defined in claim 1, wherein the guide and stop edges are provided on an extension of the rear end of the casing of the writing tool which is preferably integral with the casing itself and only surrounds a part of the pushbutton, preferably less than one half of its peripheral surface.

24. A writing tool as defined in claim 11, wherein the work surface on the upper side of the cam is downwardly inclined from the front side toward the rear side of the cam and the edges cooperating with this work surface are inclined accordingly and the work surface on the upper side of the cam engages behind these edges.

25. A writing tool as defined in claim 11, wherein the work surface on the lower side of the cam is upwardly inclined from the front side toward the rear side of the cam and the edges on the other operating member cooperating with this work surface are inclined accordingly and the work surface on the upper side of the cam engages behind these edges.

26. A writing tool as defined in claim 1, wherein the upper end of the rocker is curved slightly outwardly in the radial direction.
